WATER CLOSET COMBINATION AND WALL MOUNTING

Ralph W. Wallace, Johnstown, Pa.

Application July 21, 1933, Serial No. 681,574

7 Claims. (Cl. 4—252)

The device forming the subject matter of this application is intended to provide a frame-work wall and floor mounting for water closet combinations, whereby the closet tank and bowl may be built integral with the wall and floor construction, thereby to eliminate unnecessary and useless floor space and to provide necessary and usable floor space. A further object is to provide a handy device whereby the various room materials and finishes may be selected and readily applied. Another object of the invention is to so construct the article that it may be mounted in various positions to locate the fixtures as desired. Another object of the invention is to supply a device of the class described which will be so constructed as to guard against the accumulation of filth, germs and moisture, in the immediate vicinity of the article. A further object of the invention is to provide a device, capable of being manufactured or assembled readily, whereby various types of impervious materials may be selected and placed as to form the wall or the floor, after or at the time the unit is installed. A further object of the invention is to provide a device whereby the wall in the intermediate area about the fixture may be built of one material, and the remainder of the wall and floor be built of another material. It is another object of the invention to supply novel means whereby an integral construction can be carried out with respect to the closet bowl or other article, and the parts which support it.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in vertical section, a device constructed in accordance with the invention, parts being broken away;

Fig. 2 is a front elevation wherein the wall and floor material has been removed;

Fig. 3 is a horizontal section wherein most parts appear in top plan;

Fig. 4 is a sectional view showing a modified form of the invention;

Fig. 5 is an elevation of the structure shown in Fig. 4;

Fig. 6 is a horizontal section wherein many parts appear in elevation;

Fig. 7 is a vertical section showing a modification;

Fig. 8 is a vertical section showing a further modification;

Fig. 9 is a horizontal section showing a further modification, parts being in elevation.

In Figs. 1, 2 and 3, there is provided a support 1, composed of rectangular portions 2 and 3. The support 1 preferably is an angle iron frame, as shown in Fig. 2 of the drawings. Across the vertical part 2 of the support 1 extends an upper bar 4 and an upper bar 5. Vertical posts 6 extend between the bars 4 and 5. The bars 4 and 5 are held adjustably to the side portions of the vertical part of the support 2 by securing elements 7. An intermediate bar 8 and an intermediate bar 9 extend between the side portions of the vertical part of the support 1 and are secured thereto by attaching elements 24. A lower bar 10 and a lower bar 11 extend between the side portions of the vertical part 2 of the support, and are attached thereto, for vertical adjustment, if desired, by securing elements 12.

The numeral 14 designates a water closet bowl having a flange 25. The flange 25 is attached to the lower bars 10 and 11 by securing elements 15. The water closet bowl 14 has an outlet 16, which may be arranged as desired. As shown, but not of necessity, the outlet 16 is horizontal and extends backwardly between the bars 10 and 11. The outlet 16 carries an annular flange 17 or like face 30 provided with apertures or holes 18, adapted to receive draw bolts or clamping devices for connecting to a flexible discharge, and a flexible vented discharge or any preferred connection.

The water inlet pipe for the water closet bowl 14 is designated by the numeral 19 and may extend backwardly between the lower bars 10 and 11. The inlet pipe 19 extends upwardly, and is joined to a flush tank 20, having a water inlet 1. The flush tank 20 is secured at 21 to the intermediate bars 8 and 9. The flush tank 20 is surrounded by a cap 22. The flush tank 20 has a horizontal neck 23, which projects forwardly. The horizontal neck 23 of the flush tank 20 fits closely between the upper bars 4 and 5, and between the posts 6.

A wall forming plate 26 is secured to the forward side of the vertical part 2 of the support 1 but does not extend downwardly to the horizontal part 3 of the support 1. A floor forming 55

plate 27 is secured to the horizontal part 3 of the support 1, and has an upstanding wing 28, which extends upwardly to the lower edge of the wall forming plate 26. Although the parts 26 and 27 have been alluded to as plates, this does not mean that they have to be made of metal. They may be made of any substance, and may be finished like the balance of the room in which the device is located, or differently, according to the taste of the user. The wall forming plate 26 has a hole which receives a neck 29 extended backwardly from the flange 25 of the water closet bowl. The connection between the flange 25 of the water closet bowl 14 and the neck 29 on the one hand, and the wall forming plate 26 on the other hand, may be made hermetic, dry and perfect, by means of gaskets, cement or anything else. Over the forward end of the neck 23 of the flush tank 20, which passes through the wall forming member 26, is placed a cap 30, which may be cemented, provided with gaskets, or mounted in any other way so that there will be no leakage.

The bars 4 and 5 are adjustable upwardly and downwardly, by means of securing means 7 to accommodate tanks 20 of different lengths, and to provide a proper head of water. In the same way, the lower bars 10 and 11 may be adjusted upwardly and downwardly, by means of the securing elements 12, to vary the height of the water closet bowl 14. In the device as shown, the water closet bowl 14 is spaced from the floor, and it is obvious that the entire structure may be rendered clean and sanitary.

In Fig. 4, and in Figs. 5 and 6, the numeral 31 indicates the floor of a room, including a front wall 32, side walls 33, and a rear wall 34. There is an opening 35 in the floor 31, near to the rear wall 34. The rear wall 34 has an opening 36, communicating with the opening 35 in the floor 31. The floor 31 has an offset flange 37 at the opening 35, and the rear wall 34 has an offset flange 38 at the opening 36. The room is supported at its lower corners on angle bars 39. The room, so called, preferably may be built at the factory, and moved into the building, to fit wherever desired, on the job.

The numeral 40 indicates an angular support, corresponding to the support 1 of Fig. 1. The angular support 40 comprises a vertical part 41, and a horizontal part 42, these parts preferably being plates. The vertical part 41 of the support 40 fits against the flange 38 of the rear wall 34, in the opening 36, and the horizontal part 42 of the support 40 fits upon the flange 37 of the floor 31, within the opening 35. Securing elements 43 connect the vertical part 41 of the support 40 with the flange 38 of the rear wall 34, and securing elements 44 connect the horizontal part 42 of the support 40 with the flange 37 of the floor 31. The rear angle bar 39 is intended primarily as a support for the room or box, and is not relied upon especially for the support of the member 40.

The numeral 50 designates a water closet bowl, having a flange 45 attached by securing elements 46 to the vertical part 41 of the support 40. The outlet pipe for the water closet bowl 50 is marked by the numeral 47, and extends backwardly through the vertical part 41 of the support 40. An annular flange 48 or like member is secured to or cast integrally with the outlet 47, and has notches 49 for the reception of draw bolts or other clamping devices joining the member 48 to a similar companion member, flexibility being assured, and allowance being made for expansion, contraction, and settling of the building in which the device under consideration may be placed or erected. Any other desired connection may be used.

As shown at 51 in Fig. 5, the exposed surface of the part 41 of the support 40 may be ornamented to correspond to the ornamentation of the rear wall 34. As shown at 52 in Fig. 6, the horizontal part 42 of the support 40 may be ornamented to correspond to the ornamentation of the floor 31. In general, the matter of ornament may be left to the taste of the manufacturer.

On one or both sides of the opening 36 in the rear wall 34 there are other openings 53, provided with offset flanges 54. Access panels 55 fit in the openings 53, and are held in place by securing elements 56 engaging the flanges 54. By removing the panels 55, or the like apparatus within the walls surrounding the outlet, access is had readily to the space behind the wall 34, to facilitate connection, repair, replacement and renewal.

In Fig. 7, there is shown a room comprising a floor 57, a front wall 58, a rear wall 59, and side walls 60. The supporting angle bars 61 correspond to the angle bars 39 of Fig. 4. The angle bars 61 are not absolutely necessary, and the same observation holds true with respect to the angle bars 39.

There is an opening 62 in the floor 57, and there is an opening 63 in the rear wall 59, these openings being in communication with each other. They are adapted to receive the corresponding parts 67 and 66 of an angular support 65, resting against the flanges 64 that extend along the openings 62 and 63, the parts 67 and 66 of the support 65 being secured to the said flanges by attaching elements 68.

The water closet is marked by the numeral 69, and its flange 74 is held by securing elements 70 to the horizontal part 67 of the support 65. The outlet for the water closet 69 is marked by the numeral 71 and extends downwardly through the horizontal part 67 of the support 65. The outlet 71 carries an annular flange 72, of the kind hereinbefore described, the flange 72 being provided with slots 73 for the draw bolts (not shown) which connect the outlet 71 with the soil pipe (not shown).

In Fig. 8, the room is supported on angle bars 75, if desired, and includes a front wall 76, a rear wall 77, a floor 78, and side walls 79.

There is an opening 80 in the floor 78, communicating with an opening 81 in the rear wall 77. The floor 78 and the rear wall 77 are provided with the offset flanges 82, hereinbefore described, located along the openings. The angle support is marked by the numeral 83, and includes a horizontal part 84 and a vertical part 85. The horizontal part 84 of the support 83 fits in the opening 80, and a vertical part 85 of the support fits in the opening 81. The parts 84 and 85 are secured to the flanges 82 by attaching elements 86, or otherwise.

The water closet is marked by the numeral 87 and is formed integrally with the vertical part 85 of the support 83. The flushing rim of the water closet 87 is marked by the numeral 88. The vertical part 85 of the support 83 has an offset 89 which forms an inlet for the rim 88 of the water closet 87. To the offset 89 is secured the pipe 90 which furnishes the flushing water, and this pipe may be led wherever desired. The outlet is marked by the numeral 91 and is formed inte-

grally with the water closet bowl 87 and with the vertical part 85 of the support 83. The outlet 91 carries the notched annular flange 92 of the kind hereinbefore described, or an equivalent device.

In Fig. 9, the floor of the room is shown at 93, and the rear wall appears at 94. The access panels or the like 95, which are removable, are secured at 96, to the offset flanges 97 on the rear wall 94.

The opening in the rear wall 94 is marked by the numeral 98, and the opening in the floor 93 is marked by the numeral 99. The support is designated by the numeral 101, and is of angular form, as hereinbefore described. The support 101 comprises a horizontal portion 104 and a vertical portion 105. The vertical portion 105 of the support 101 fits in the opening 98 of the wall 94, and the horizontal part 104 of the support 20 fits in the opening 99 of the floor 93. The offset flanges 100 or the like are used, as before described, or otherwise, and securing elements 102 connect the parts 104 and 105 of the support 101 with the flanges 100. The parts mentioned may be eliminated, and cement substituted.

The water closet is marked by the numeral 106, and has a flange 107, connected by securing elements 108 to the vertical part 105 of the support 101. The outlet for the water closet 106 is marked by the numeral 109, and has a notched annular flange 110, of the kind hereinbefore described.

Noting in the places where the reference numerals 111 and 112 are applied, it will be observed that the upper surface of the horizontal part 104 of the support 101 need not be finished like the upper surface of the floor 93, although these are matters which can be left to the manufacturer.

In all forms of the invention, a highly sanitary and cleanly structure is provided and the floor and wall about all parts of the structure may be kept in a clean and desirable condition with a minimum amount of effort.

Having thus described the invention, what is claimed is:

1. In a device of the class described, an angular support comprising horizontal and vertical parts, the vertical part being adapted to form part of the wall of a room, and the horizontal part being adapted to form part of the floor of the room, the vertical part having free vertical outer edges located in the same plane with said vertical part, and the horizontal part having free horizontal outer edges located in the same plane with said horizontal part, and a toilet fixture carried by the vertical part.

2. In a device of the class described, an angular support comprising horizontal and vertical parts, the vertical part being adapted to form part of the wall of a room, and the horizontal part being adapted to form part of the floor of the room, the support being in the form of an open frame, a water closet carried by the vertical part of the frame, a flush tank communicating with the water closet, the flush tank being provided with a forwardly prolonged neck, and the vertical part of

the support having spaced bars between which the neck is received.

3. In a device of the class described, a support comprising horizontal and vertical parts, the vertical part being adapted to form part of the wall of a room, and the horizontal part being adapted to form part of the floor of a room, the vertical part having free vertical outer edges located in the same plane with said vertical part, and the horizontal part having free horizontal outer edges located in the same plane with said horizontal part, and a water closet bowl carried by the vertical part of the support, the water closet bowl having an outlet extended backwardly through the vertical part of the support.

4. In a device of the class described comprising an angular support including horizontal and vertical parts, a wall and a floor, the vertical part fitting into the wall, and the horizontal part fitting into the floor, the vertical part having free vertical outer edges located in the same plane with said vertical part, and the horizontal part having free horizontal outer edges located in the same plane with said horizontal part, means for securing the support in place in the wall and in the floor, a toilet appliance carried by the vertical part of the support, and an access panel in said wall, at one side of the vertical part of the support.

5. In a device of the class described, an angular support, comprising horizontal and vertical parts, the vertical part being adapted to form part of the wall of a room, and the horizontal part being adapted to form part of the floor of the room, the vertical part having free vertical outer edges located in the same plane with said vertical part, and the horizontal part having free horizontal outer edges located in the same plane with said horizontal part, and a toilet fixture carried exclusively by one of said parts of the support.

6. In a device of the class described, an angular support, comprising horizontal and vertical parts, the vertical part being adapted to form part of the wall of a room, and the horizontal part being adapted to form part of the floor of the room, the vertical part having free vertical outer horizontal edges located in the same plane with said vertical part, and the horizontal part having free horizontal outer edges located in the same plane with said horizontal part, and a toilet fixture carried exclusively by the vertical part and supported thereby.

7. In a device of the class described, an angular support, comprising horizontal and vertical parts, the vertical part being adapted to form part of the wall of a room, and the horizontal part being adapted to form part of the floor of the room, the vertical part having free vertical outer edges located in the same plane with said vertical part, and the horizontal part having free horizontal outer edges located in the same plane with said horizontal part, and the toilet fixture carried exclusively by and supported exclusively by the horizontal part.

RALPH W. WALLACE.
